UNITED STATES PATENT OFFICE.

EDWARD B. DEWEY, OF WASHINGTON, DISTRICT OF COLUMBIA.

HAIRPIN CONTAINER.

Application filed January 25, 1921. Serial No. 439,729.

To all whom it may concern:

Be it known that I, EDWARD B. DEWEY, a citizen of the United States, residing at Washington, in the District of Columbia, have invented certain new and useful Improvements in Hairpin Containers; and I hereby declare that the following is a full, clear, and exact description thereof, reference being had to the accompanying drawings, which form part of this specification.

This invention relates to foldable containers, and consists in a novel, useful and ornamental container for small articles, such as hairpins and the like.

An object of the present invention is to provide a foldable container which can be manufactured in quantities at small cost. The finished container is neat and of small size and is particularly adapted to be utilized for packing hairpins which are to be placed on sale, and also to provide the purchaser thereof with a convenient attractive and durable container for hairpins or like articles, which may be readily carried in the purse or handbag. The containers may be made of any suitable material such as colored paper or pasteboard and may be provided with ornamental designs of various kinds to enhance their attractiveness both when displayed for sale and when in use.

Other objects of my invention will appear hereinafter and the claims summarize the invention for which I desire protection.

In the drawings:

Fig. 1 is a view of the completed container, opened.

Fig. 2 is a view of the container closed, with folded flaps and fastenings indicated in dotted lines.

Fig. 3 is an enlarged transverse sectional view on the line 3—3, Fig. 1, looking in the direction of the arrows.

Fig. 4 is a view of the container blank before it has been folded.

The container as shown in the drawing is preferably formed of suitable flexible material. For cheapness I would use tough paper. The container is preferably formed of one piece of material. It has a back 1, opposed side flaps 2 and 3; a top flap 4; and a pocket or pockets 5. The pocket is formed preferably by an inner strip of material upon itself, so that the lower portions of the flaps 2 and 3 are of double thickness for the height of the pocket. Preferably the op-

posed thicknesses of the material throughout the flaps 2 and 3 are pasted together for the full extent of the inner portion of each side flap so as to strengthen and stiffen the side flaps, but the portion of the inner strip of material opposite the part 1 and between the inner edges of the flaps 2 and 3 is not pasted to part 1 and this folded portion of the material and the opposed portion of the back 1 form between them the pocket or pockets 5.

A suitable blank from which the container may be formed is shown in Fig. 4. This blank has sections 1 and 4 corresponding in location and size to the back 1 and flap 4. At each side of the section 1 this blank has sections 2^a, 3^a corresponding in location and size to flaps 2 and 3. Below these parts the blank has a section 1^a shorter than the section 1 and integral therewith at its meeting end; and at opposite sides of the part 1^a the blank has sections 2^b, 3^b which unite with the lower ends of sections 2^a, 3^a and substantially correspond to but are shorter than the flap sections 2^a, 3^a. The section 3^a is provided on its outer edge with a hook portion 6^a and the section 3^b is provided on its outer edge with a reverse hook portion 6^b.

This blank is folded on the dotted line a so as to bring the portions 2^a, 1^a, 3^b, and 6^b over and against the portions 2^a, 1, 3^a and 6^a. The sections 2^a, 2^b are then pasted together, so are the sections 3^a, 3^b, and when so pasted together form the flaps 2 and 3 (Fig. 1). The book sections 6^b, 6^a registered when the parts are properly folded and are pasted together and form a hook 6 projecting from the edge of the flap 3 (Fig. 1) which hook is adapted to engage a slit 7 in the flap 2; which slit may be formed in the blank prior to folding it, by perforating the portions 2^a, 2^b as indicated at 7^a, 7^b, Fig. 4.

When the parts are thus folded and fastened the parts 1^a and 1 not being united form a pocket between them. This may be one single pocket or if desired the part 1^a may be pasted to the back 1, as indicated in dotted lines 8, Fig. 1; or stitched thereto as indicated at 8^a, Fig. 3, thus forming two pockets. Of course the size and number of pockets will depend upon the size of the container and preference of the maker.

The container shown is particularly adapted to hold hair pins, which may be readily inserted in the pockets. The flap 4 may be folded down over the mouth of the

pocket as indicated in dotted lines in Fig. 2, then the flap 2 folded over the pocket and flap 4; and then the flap 3 folded over the flaps 4 and 2; and the hook 6 engaged with 5 the slit 7 as indicated in Fig. 2; thus locking the parts together.

By this construction the flaps 2 and 3 are rendered very durable because of their double thickness. The pocket is ample; the 10 articles are protected from falling out of the pockets by the flap 4; and the container can be folded into a complete neat looking package as indicated in Fig. 2.

The container can be made very cheaply 15 and is particularly adapted for the purposes before described, and may also be used for many other purposes much in the manner of a pocket-book or the like.

What I claim is:

- 20 1. A foldable container of the character described, formed of a blank of suitable material having one portion folded back upon itself and fastened at its sides to the other portion so as to form a pocket therebetween; 25 a flap on the opposite end thereof adapted to be folded toward the top end of said pocket; a flap at one side of said pocket adapted to be folded over the pocket; a flap at the other side of the pocket adapted to be folded over 30 the pocket; and means for detachably attaching the side flaps together when folded, substantially as described.
2. A container for the purpose specified 35 formed of foldable material comprising a back, a top flap, and opposed side flaps, and an inner portion extending across the back and inner face of both side flaps, the parts of this inner portion overlying the side flaps being attached thereto to reinforce the side 40 flaps, and the part of the inner portion opposite the back forming therewith a pocket; the top flap being foldable over the pocket,

and the opposed flaps being folded over the top flap one over the other and such side flaps being provided with engaging means 45 for detachably holding them in folded position.

3. A container for the purpose specified formed of foldable material comprising a back, a top flap, and opposed side flaps, and 50 an inner portion extending across the back and inner face of both side flaps, the part of the inner portion opposite the back forming therewith a pocket, and the top flap being foldable over the pocket; and one of the side flaps being foldable over the top flap and the pocket, and the other side flap being foldable over the top flap and the opposed side flap, 55 said side flaps being provided with integral means for detachably holding them in folded position, substantially as described.

4. A container for the purpose specified 60 formed of foldable material comprising a back, a top flap, and opposed side flaps, and an inner portion extending across the back and inner face of both side flaps, the said 65 inner portion being formed integral with the other portions of the container and the parts of said inner portion overlying the side flaps being pasted thereto to reinforce the side 70 flaps, and the part of the inner portion opposite the back forming therewith a pocket, the said top flap being foldable over the pocket, and one of the opposed side flaps being 75 foldable over the top flap and the pocket, and the other side flap being foldable over the top flap and the opposed side flap, said side flaps being provided with integral 80 means for detachably holding them in folded position, substantially as described.

In testimony that I claim the foregoing as my own, I affix my signature.

EDWARD B. DEWEY.
